(57) **CLAIM**

The ornamental design for a colander, as shown and described.

DESCRIPTION

FIG. 1 is a perspective view of a first embodiment of the colander according to the present invention.

FIG. 2 is a front view of the embodiment of the colander shown in FIG. 1, the rear view being identical.

FIG. 3 is a side view of the embodiment of the colander shown in FIGS. 1 and 2, each side view being identical.

FIG. 4 is a top view of the embodiment of the colander shown in FIGS. 1-3.

FIG. 5 is a bottom view of the embodiment of the colander shown in FIGS. 1-4.

FIG. 6 is a perspective view of a second embodiment of the colander according to the invention.

FIG. 7 is a front view of the embodiment of the colander shown in FIG. 6, the rear view being identical.

FIG. 8 is a side view of the embodiment of the colander shown in FIGS. 6 and 7, each side view being identical.

FIG. 9 is a top view of the embodiment of the colander shown in FIGS. 6-8.

FIG. 10 is a bottom view of the embodiment of the colander shown in FIGS. 6-9.

FIG. 11 is a perspective view of a third embodiment of the colander according to the present invention.

FIG. 12 is a front view of the embodiment of the colander shown in FIG. 11, the rear view being identical.

FIG. 13 is a side view of the embodiment of the colander shown in FIGS. 11 and 12, each side view being identical.

FIG. 14 is a top view of the embodiment of the colander shown in FIGS. 11-13; and,

FIG. 15 is a bottom view of the embodiment of the colander in FIGS. 11-14.
